SAFETY RAZOR

Filed April 20, 1931

INVENTOR
Nicholas Testi
BY G. F. Bourne
ATTORNEY

UNITED STATES PATENT OFFICE

NICHOLAS TESTI, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed April 20, 1931. Serial No. 531,316.

My invention relates to improvements in safety razors and is particularly applicable to the class of safety razors having double edge blades held in shaving position between clamping members.

An object of my invention is to provide a blade with novel means to position itself in cooperation with one of the clamping members with its edges in shaving relation to the guard.

In carrying out my invention I provide a blade having integral projections extending at angles to the plane of the blade and so positioned as to permit the side portions of the blade adjacent to the cutting edges to be flexed in a blade holder, whereby when the blade is placed against one of the clamping members of a safety razor the projections will not interfere with the proper clamping and bending of the blade in the holder.

My invention also comprises novel details of improvement that will be hereinafter more fully set forth and then pointed out in the claims.

Reference is to be had to the accompanying drawings wherein:

Fig. 1 is a side view of a safety razor embodying my invention;

Fig. 2 is a section on line 2, 2 in Fig. 1;

Fig. 3 is a perspective view of my improved blade;

Fig. 4 is a partly broken plan view, in section on line 4, 4 in Fig. 2;

Fig. 5 is a plan view of the guard member;

Fig. 6 is a plan view of a modified form of blade;

Fig. 7 is an edge view of Fig. 6;

Fig. 8 is a sectional view of a razor including the blade of Fig. 6;

Fig. 9 is a plan view of the guard member of Fig. 8; and

Fig. 10 is a plan view of another form of blade.

Similar numerals indicate corresponding parts in the several views.

My improved blade is indicated at 1, the same being shown provided with cutting edges 1a along opposite sides in a well known way. The blade is shown provided

with projections 2 that extend angularly and obliquely therefrom in a lateral direction, preferably both projections extending from same side of the blade and in opposite directions. The projections 2 are shown located in the plane of the central portion of the blade, whereby the portions 3 of the blade that are between the cutting edges and the projections 2 may be flexed suitably for adjustment with respect to the guard of the razor for shaving. In the form shown in Figs. 1 to 4 the blade is provided with slots 4 extending inwardly from the ends of the blade adjacent to the projections 2, in a longitudinal direction, whereby the marginal portions 3 of the blade may be flexed freely.

The blade 1 is adapted to be clamped in a blade holder of a safety razor in a well known way, and the projections 2 are adapted to cooperate with one of the clamping members of the blade holder to retain the blade in shaving position with respect to the guard member. 5 indicates a guard member and 6 a cap or backing member for the blade, and 7 indicates a handle. The parts 5, 6 and 7 may be connected together for clamping the blade between the guard member and the cap or backing member in any desired way. I have illustrated the cap as provided with a threaded stem 8 operative in a threaded recess 8a in handle 7, whereby the blade may be clamped between the members 5 and 6 in a well known way.

One of the members, such as the guard member, is provided with means to cooperate with the projections 2 of the blade to retain the blade between the members 5 and 6 with the cutting edges of the blade in shaving position with respect to the guard teeth. In the form shown in Figs. 1 to 5 the guard member 5 is shown provided at its ends with oblique plane surfaces 9 against which the projections 2 of the blade are adapted to fit to retain the blade in shaving position on said member. The surfaces 9 are shown located at an angle with respect to the plane of the blade receiving surface 10 of the guard member, and extend in the direction of the projections 2, whereby when the blade is laid upon said surface 10 with the projections 2 in engagement

with the surfaces 9 the blade will be retained from edge-wise and endwise displacement. The blade is shown provided with a centrally disposed aperture 11 for the passage therethrough of the stem 8, and the guard member 5 is shown provided with an aperture 10a that will register with the aperture 11 of the blade for the passage of said stem.

To retain the cap or backing member 6 in shaving relation to the guard edges any desired means may be provided. I have illustrated the cap 6 as provided with studs 12, spaced on opposite sides of the stem 8, said studs being adapted to pass through the apertured portions 11a of the blade and into openings 13 in the guard member. The studs 12 are adapted to engage the guard member at the openings 13 to retain the cap in shaving position against the blade. The studs are shown provided with outer end portions 12a, of dimensions to fit the openings 13 of the guard and said studs are also shown provided with reduced portions 12b between the enlarged end portions 12a and the cap, whereby if a blade having stud receiving apertures that will receive the head portions 12a of the studs be placed upon the guard member, which blade is not provided with projections to engage the guard member to retain it in shaving position thereon, said blade will not be retained by the studs in shaving positions on the guard because the reduced portions 12b of the studs will not properly engage said apertures of the blade, and the latter will be loose on the guard and will not be guided by the studs.

Referring to Figs. 6 to 9, the projections 2 from the blade, instead of being at the ends of the latter, are located within the boundaries or marginal edges of the blade and project laterally therefrom at angles thereto to engage the guard member. In Fig. 6 the projections 2 are illustrated as stamped from the material of the blade by means of slits 2a of the blade, leaving inner portions of the projections attached to the blade material. The projections 2 are shown bent outwardly from the blade and are adapted to enter openings 13a in the guard member, (Fig. 9). The openings 13a are sufficiently long to receive the projections 2, as in Fig. 8, and the widths of the projections 2 and of the openings 13a in the guard substantially correspond in such a way that when said blade is placed against the guard and the projections 2 enter the openings 13a said projections will cooperate with the sides of said openings to retain the blade in shaving position on the guard. The slits 2a, have portions extending longitudinally substantially parallel to the cutting edges of the blade, permitting the portions 3 of the blade to readily flex when clamped between the members 5 and 6 of the razor.

It will be noted that the inner surfaces of the openings 13a constitute oppositely in-

clined, blade-locating faces to correspond to the surfaces 9 in the embodiment of my invention shown in Figs. 1 to 5. The projections or tongues 2 of the blade are shaped to conform to these faces and to locate the blade accurately by their engagement therewith. The openings 13a are also designed to fit the enlarged heads 12a of the studs and these positively determine the relative position of the two blade-clamping members. When the blade is positioned upon the guard member 5, its tongues 2 extend below or beyond the heads 12a of the studs.

In Fig. 10 the blade is distinguished from the blade shown in Fig. 3 by the absence of the slits 4, yet the marginal portions 3 of the blade of Fig. 10 may flex between the cutting edges and the adjacent ends or edges of the projections 2 for properly clamping the blade between members 5 and 6 of the blade holder 36 the projections 2 cooperating with the end surfaces 9 of the guard member in manner shown in Fig. 2.

When my improved blade is placed on the guard the projections 2 of the blade will position the latter with its cutting edges in shaving relation to the guard teeth, and when the cap 2 is clamped against the blade, as in Figs. 1, 2 and 8, the blade will be retained for shaving, the blade being bent or flexing in a desired way when clamped in position for shaving.

Having now described my invention what I claim is:

1. A safety razor comprising blade clamp-
ing members and means to clamp said mem-
bers against a blade, one of said members
having surfaces at its end located at an
oblique angle to the blade receiving surface of
said member, and a blade having projections
at its ends extending at a correspondingly
oblique angle to the blade to engage the first
named surfaces of said member to position
the cutting edges of the blade in shaving
relation to said member. 30

2. A safety razor as set forth in claim 1 in
which one member is provided with openings
and the other member is provided with studs
adapted to fit said openings, the blade being
apertured to receive said studs. 105

3. A safety razor comprising blade clamp-
ing members, means to clamp said members
against a blade, one of said members having
studs, the other member having openings to
receive said studs, and an internally aper-
tured blade having projections extending at
an angle therefrom to cooperate with said
member to position the blade in shaving rela-
tion to said member, said studs having re-
duced portions adapted to loosely receive the
apertures of said blade. 120

4. A safety razor comprising blade clamp-
ing members, means to clamp said members
against a blade, one of said members having
longitudinally extending openings, the other 230

member having studs adapted to fit within said openings to retain said members in shaving relation, and a blade having laterally extending projections adapted to fit said openings to retain the blade in shaving relation to the member having said openings.

5. A safety razor blade adapted to be clamped in a position of transverse curvature for shaving, and comprising a normally flat body portion sharpened at its longitudinal edges and having longitudinal slots at its ends spaced from said edges and defining between them an unsharpened tongue extending obliquely with respect to the body of the

15 blade.

6. A safety razor blade adapted to be clamped in a position of transverse curvature for shaving, and comprising a normally flat body portion sharpened at a longitudinal edge 20 and having slots extending inwardly from each end and defining between them an elongated unsharpened tongue which is bent at an oblique angle to the plane of the blade.

7. A safety razor blade adapted to be clamped in a position of transverse curvature for shaving, and comprising a body portion with exterior sharpened edges and parallel, longitudinally-extending slots spaced within said cutting edges and defining between them 30 a tongue extending at an oblique angle in the body of the blade which is free of transverse bending with the body of the blade.

8. A safety razor comprising co-operating blade-clamping members, one having elongated slots with oppositely inclined blade-locating surfaces, and the other having studs arranged to fit within the slots, and a blade having inclined locating tongues adapted to fit upon the blade-locating surfaces of said 40 slots and to extend beyond the ends of said studs.

NICHOLAS TESTI.
